UNITED STATES PATENT OFFICE.

ERNEST W. HOPPER, OF SEATTLE, WASHINGTON, ASSIGNOR TO HOPPER CANNERY MACHINERY CO., OF SEATTLE, WASHINGTON, A CORPORATION OF WASHINGTON.

CAN-COOLING DEVICE.

1,420,841.

Specification of Letters Patent. Patented June 27, 1922.

Application filed January 19, 1920. Serial No. 352,642.

To all whom it may concern:

Be it known that I, ERNEST W. HOPPER, a citizen of the United States, residing at Seattle, in the county of King and State of 5 Washington, have invented a certain new and useful Improvement in Can-Cooling Devices, of which the following is a specification.

My invention relates to improvements in 10 apparatus for cooling tin cans that are filled with cooked food after such cans have been removed from a retort or cooking oven and the object of my invention is to provide a cooling apparatus that is adapted to receive the heated cans from a retort and subject 15 them to a cooling blast of air for a long enough period of time to thoroughly cool such cans.

A further object is to provide a can cooling device that may be connected with a retort from which cans are being discharged continuously and which will receive such cans and subject them to a cooling process.

A still further object is to provide a can 25 cooling device that is simple in its plan of construction, efficient in operation, inexpensive to build and that has few mechanical parts to get out of order.

My invention consists in the novel construction, adaptation and combination of 30 parts of a can cooling apparatus as will be more clearly hereinafter described and claimed.

I accomplish these objects by devices illustrated in the accompanying drawings 35 wherein—

Figure 1 is a view in side elevation of a can cooling device constructed in accordance with my invention;

40 Fig. 2 is a detached plan view of the can carrying cage substantially on broken line 2, 2 of Fig. 1 certain parts being broken away;

Fig. 3 is a view in cross-section on broken 45 line 3, 3 of Fig. 1 and

Figure 4 is a cross sectional view taken on line IV—IV of Fig. 1.

Referring to the drawings, throughout 50 which like reference numerals indicate like parts, the numerals 5 and 6 designate two end headers that are fixedly mounted in spaced apart relation on an inclined shaft 7 that is journaled in bearings 8 and 10.

The headers 5 and 6 each comprise a hub 55 portion 11 that is secured to the shaft 7, a

spoked or webbed portion 12 that permits free passage and circulation of air therebetween and a relatively wide rim portion 13, as more clearly shown in Fig. 3.

A plurality of can conduits or trackways 60 14 that are each preferably formed of four angle bars arranged in spaced apart relation at the four corners of each trackway 14, shown in Fig. 3, the angle bars being spaced apart to permit the free circulation 65 of air within the trackways 14 and said trackways being inclined just enough to cause the cans to roll freely from the inlet to the discharge end thereof.

In Fig. 2 I have shown a portion of the 70 header broken away and have shown the angle bars of which the trackways are formed as extending through rectangular openings 15 in such headers and being rigidly secured to the side walls of such openings so that the trackways 14 are open to receive cans from a can inlet chute 16 at the head end of the machine and to discharge cans into a discharge chute 17 at the discharge end of the machine. 75

The headers 5 and 6 have rigid or stationary annular plates 20 and 21, respectively, disposed in relatively light engagement with the outer sides thereof, as shown in Figs. 1 and 2, to prevent the inlet and exit of cans except through the inlet and discharge chutes 16 and 17. The annular plates 20 and 21 are adapted to be fixedly secured in any well known manner to the bearings 8 and 10 at points 20^a and 21^a respectively. 80

The inlet and discharge chutes project through suitable notches 22 formed in the support end plates 20 and 21 and are offset a distance equal to the distance between two 95 successive trackways with respect to each other so that as the cage formed by the two end plates 5 and 6 and the trackways 14 is rotated in the direction, shown by the arrow, cans will be admitted to one trackway 100 from the chute 16 and will be retained therein while the cage is making almost one complete revolution or until the same trackway is moved into registration with the discharge chute 17 and said cans are permitted 105 to roll out.

The cage formed by the headers 5 and 6 and the trackways 14 is arranged to be rotated by a pawl 23 having a slot 24 in its lower end that fits over a shaft 25 that 110

carries a rigidly mounted cam 26 having a curved surface 27 that is arranged to engage with a pin 28 in the pawl 23 and lift said pawl from the position shown by full 5 lines to the position shown by dotted lines in Fig. 3, each time the shaft 25 is turned through one complete revolution thereby rotating the cage an amount equal to the distance between two successive trackways 14.

10 The upper end of the pawl 23 is arranged to engage with teeth or shoulders 30 in a band 31 that is secured to and encircles the several trackways 14 and the pawl 23 is normally held in engagement with said 15 band 31 by a spring 32.

The shaft 25 is journaled in suitable bearings 33 and may be connected with any suitable driving mechanism, not shown, by which it may be rotated at a predetermined speed which will leave the cans in 20 the trackways 14 for a long enough period of time to thoroughly cool them.

Air for cooling purposes may be supplied to the can cooler by a fan 34 that is rigid 25 on a shaft 35 that is journaled in a bearing 36 and is connected by a belt 37 with a motor 38 by which it may be driven.

The fan 34 shown in the drawings, is located at the inlet or head end of the machine 30 but it will be understood that the same may be located at any other point, if desired, so long as all parts of the trackways are subjected to the blast of cooling air therefrom.

In operation, heated cans are delivered 35 into the chute 16 so that they will tend to roll by gravity down said chute. As soon as an empty trackway 14 is moved opposite the chute 16 the cans will roll thereinto and fill said trackway and will 40 be retained therein until the trackway has been moved around almost one complete revolution or until it registers with the can outlet chute 17 whereupon the cans will be permitted to roll out thereby leaving said 45 trackway empty and in condition to again be filled with heated cans upon the next progressive movement thereof which will bring it into registration with the inlet chute 16.

50 In the manner above described, a batch of heated cans may be delivered into one trackway and a batch of cooled cans discharged from another trackway at each progressive forward movement of the can 55 carrying cage thus making the process continuous.

The cam 26 is shaped so that it will raise the pawl 23 from the lowermost to the uppermost limit of its movement while the 60 shaft 25 is being turned through a relatively small angle thus allowing the can carrying cage to remain at rest with one trackway in registration with the inlet chute and another trackway in registration 65 with the outlet chute throughout the greater

portion of the time consumed by each complete revolution of the shaft 25.

When the device is in operation all of the trackways except the one that is in registration with the discharge chute 17 will 70 normally be filled with cans.

Obviously, changes may be made in the forms, dimensions and arrangement of parts of my invention without departing from the spirit thereof.

75

What I claim is:

1. In a can cooling device, a plurality of trackways formed of longitudinal corner rods defining lateral open spaces and means for directing a blast of air over and through 80 said trackways.

2. In a can cooling device, a plurality of trackways inclined with respect to the horizontal and formed of longitudinal corner rods defining lateral open spaces, and means 85 for directing a cooling blast of air over and through said trackways.

3. In a can cooling device, a can carrying cage comprising a plurality of relatively fixed trackways arranged for rotation 90 about an axis that is inclined with respect to the horizontal and formed of longitudinal corner rods defining lateral open spaces, and means for directing a cooling blast of air over and through said trackways.

4. A can cooling device comprising a can carrying cage formed of a plurality of trackways arranged in relatively fixed cylindrical relation and rotatable about an axis that is inclined slightly with respect to 100 the horizontal and formed of longitudinal corner rods defining lateral open spaces, and means for directing a cooling blast of air lengthwise through said cage and trackways.

105

5. A can cooling device, comprising a cage formed of a plurality of trackways fixed with respect to each other and arranged in substantially cylindrical spaced apart relation and formed of longitudinal 110 corner rods defining lateral open spaces, means supporting said cage for rotation about an axis that is inclined slightly with respect to the horizontal, means for rotating said cage, a device for delivering cans 115 into one end of said trackways as said cage is rotated, another device for receiving cans from the opposite end of said trackways, and means for directing a cooling blast of air over and through said trackways.

120

6. A device of the class described, comprising a cage formed of two headers disposed in spaced apart parallel relation, a plurality of trackways secured to said headers and extending therebetween in substantially cylindrical relative fixed spaced apart relation, and formed of longitudinal corner rods defining lateral open spaces, said trackways having open passageways at each end through said headers, means supporting said 125 130

cage for rotation about an inclined axis, means for rotating said cage, a fixed plate adjacent the header at the discharge end of said cage, a discharge chute projecting through said fixed plate and arranged to successively register with the open ends of said trackways when said cage is rotated, an inlet chute at the opposite end from said discharge chute and arranged to successively register with said trackways after they have passed the position of registration with said discharge chute and means for directing a blast of air lengthwise through said cage and trackways.

In witness whereof, I hereunto subscribe my name this 31st day of December, A. D. 1919.

ERNEST W. HOPPER.
